UNITED STATES PATENT OFFICE.

ANDRIES WILLEM JANSEN, OF GELDROP, NETHERLANDS.

APPARATUS FOR WEAVING BICYCLE AND AUTO CANVAS.

1,423,427.

Specification of Letters Patent. Patented July 18, 1922.

Application filed December 18, 1921. Serial No. 522,074.

To all whom it may concern:

Be it known that I, ANDRIES WILLEM JANSEN, engineer, residing at Geldrop, Netherlands, have invented certain new and useful Improvements in Apparatus for Weaving Bicycle and Auto Canvas, of which the following is a specification.

The invention relates to a novel construction and arrangement of apparatus for weaving bicycle and auto canvas, a textile fabric having relatively few weft threads. Heretofore it has been customary in weaving such materials to wind the warp threads upon warp beams and then introduce them into the loom. The substitution of a full warp beam for an empty one necessitated stopping of the loom, resulting in loss of production. Moreover, the preparation of the warp beam required the help of a skilled workman, the weaving master, thereby adding to the cost of production. Furthermore, it often happened that the first tissue was unserviceable and the last portion of the warp, the so-called drum, was lost. Besides, the last portion of the warp threads was lost during warping and beaming up.

The above-mentioned drawbacks are avoided by the present invention according to which the warp threads, without being beamed up, are fed from one or more creels of novel construction to a novel form of tension device. The advantages of the invention are many. By reason of the omission of preparatory machines and the weaving beams, fewer workmen are required and there are practically no losses of material and the working is continuous owing to the fact that the empty bobbins of the warp threads may be gradually replaced by full bobbins during weaving.

The drawings illustrate one embodiment of the invention by way of example.

Fig. 1 shows schematically a side elevation of the device with the loom.

Fig. 2 is a plan view of this device, without the loom.

Fig. 3 shows on a larger scale a front elevation of a thread frame with some bobbins and thread guides mounted on the same.

According to the invention the warp threads of the bobbins, placed upon the thread frames 1, are fed through the reed 2 to a feeding or brake device, consisting of a roller 3, having a covering of a friction-material, e. g. felt, with front and back tension rollers 4 and 5. This device is con-

structed in such a manner, that the warp threads are subjected to sufficient friction, while however it is still possible to draw through each thread individually without danger of rupture, which is important in repairing threads and removing eventual mistakes in the threads. From here they pass over the smoothing beam 6 to the loom, indicated as a whole by 7 in Fig. 1. The reed 2 is mounted more or less resiliently e. g. on a brace 8. The felt covered roller 3 acts as a feeding or brake device, so that an equal feeding of the warp threads is obtained.

The resilient suspension of the reed contributes to the warp discharge and decreases the danger of rupture.

As appears from Fig. 2 the frames may be very long so that the height may be so small, that all bobbins are within the reach of a boy or girl, whereas nevertheless a very large number of bobbins may be mounted on the frames.

For obtaining an easy substitution of empty bobbins by full ones the bobbin pins 9 at both sides are placed perpendicular to the planes of V-shaped carriers 10, which are secured to the vertical frames 1, so that the bobbins 12 are disposed under an angle of about 45° with respect to the vertical plane.

From the bobbins the warp threads run through eyes in the thread guides 13 in such a manner, that each thread is guided in its own eye.

By this device it results that in the case of a rupture of a thread, the broken thread can be found directly and repaired by the assistant without interruption of the work.

Claims:

1. Weaving apparatus, comprising a tension device and a plurality of spaced creels arranged in front of said tension device, said tension device comprising a plurality of cooperating rollers and a reed yieldingly supported in front of said rollers, and each of said creels comprising a carrier extending radially with respect to said tension device, and a row of bobbin pins supported by said carrier.

2. Weaving apparatus, comprising a tension device, and a plurality of spaced creels arranged in front of said tension device, said tension device comprising a plurality of cooperating rollers and a reed yieldingly supported in front of said rollers and each of said creels comprising a carrier extending

radially with respect to said tension device, a row of bobbin pins supported by said carrier, and a member at the front of said carrier and extending laterally thereof, 5 said member being provided with a plurality of guiding eyes for the individual warp threads carried by the bobbins supported in said carrier.

3. In weaving apparatus, a unitary tension device, comprising a supporting frame, 10 a roller journaled in said frame and hav-

ing a covering of friction material, tension rollers having a relatively small diameter in comparison to the diameter of the friction roller, said tension rollers being arranged 15 at the front and back of said friction roller and in close proximity thereto, a reed in front of said friction roller, and yielding means supporting said reed from said frame.

In testimony whereof I affix my signature. 20

ANDRIES WILLEM JANSEN.
